UNITED STATES PATENT OFFICE.

PAUL E. HAWKINSON, OF MINNEAPOLIS, MINNESOTA.

ATTACHMENT FOR LIFTING JACKS.

Application filed August 18, 1921. Serial No. 493,308.

To all whom it may concern:

Be it known that I, PAUL E. HAWKINSON, a citizen of the United States, residing at Minneapolis, in the county of Hennepin and State of Minnesota, have invented certain new and useful Improvements in Attachments for Lifting Jacks; and I do hereby declare the following to be a full, clear, and exact description of the invention, such as will enable others skilled in the art to which it appertains to make and use the same.

My present invention has for its object to provide an extremely simple, light and highly efficient carrying and positioning attachment for lifting jacks, intended for general use but especially adapted for use in jacking up the wheels of automobiles and trucks at tire and tire-repairing stations and garages.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a side elevation of a lifting jack having the improved attachment applied thereto;

Fig. 2 is a plan view of the parts shown in Fig. 1;

Fig. 3 is a detail view with some parts sectioned on the line 3—3 of Fig. 2, on an enlarged scale;

Fig. 4 is a detail view in section taken on the line 4—4 of Fig. 2, on an enlarged scale;

Fig. 5 is a view corresponding to Fig. 1 and illustrating a modified form of the attachment; and

Fig. 6 is a detail view with some parts sectioned on the line 6—6 of Fig. 5, on an enlarged scale.

For the purpose of illustrating the invention, there is shown in the drawings a standard lifting jack 7 having an operating shaft 8, to the projecting end of which is attached, by a universal joint 9, a two-part folding operating rod 10, the sections of which are connected by a hinge joint 11. To the outer end of the operating rod 10 is applied a hand crank 12 having a hinge joint 13, which permits said hand crank to be folded onto the operating rod 10.

Referring now in detail to the invention as disclosed in Figs. 1 to 4, inclusive, the at-

achment includes a skeleton frame made up of a pair of laterally spaced side rods 14 connected by front and rear U-bolts 15. These side rods 14 and U-bolts 15 are adapted to embrace the standard of the lifting jack 7, as best shown in Fig. 2, and which lifting jack is detachably secured to the attachment by frictionally clamping the side rods 14 thereon by U-bolts 15.

The frame side rods 14 are bent to form pairs of front and rear spring coils 16 and 17, respectively, and which side rods, at the front spring coils 16, are bent downwardly and rearwardly to afford a pair of arms 18 having rigidly secured thereto an axle 19 on which is journaled a pair of frame-supporting wheels 20. At the rear pair of spring coils 17, the frame side rods 14 are extended rearwardly and upwardly to afford extensions 21 and then bent first downward, then forward and then upward and forward to afford a pair of rear runners 22. By reference to Fig. 2, it will be noted that these runners 22 diverge laterally and thereby give stability to the attachment and support the same in an upright position. The frame side rod extensions 21, at their rear ends, are connected by a pair of bearing plates 23 in which the operating rod 10 is journaled. These bearing plates 23 are connected by nut-equipped bolts 24, which, together with the curved outer ends of said plates, securely hold the frame side rod extensions 21.

The attachment illustrated in Figs. 5 and 6 is a simplified form of the attachment shown in Figs. 1 to 4, inclusive, and, in this attachment, the rear runners 22 are dispensed with. In this construction, the side rod extensions 21 are extended only a short distance back of the rear spring coils 17 and connected by a transverse portion 25, which is folded upon itself to form a spring U-shaped clip 26 adapted to receive and frictionally hold the operating rod 10, as best shown in Fig. 6.

From the above description, it is evident that the attachment may be very easily and quickly applied to the standard of a lifting jack or removed therefrom. By the use of the attachment, a lifting jack may be wheeled to any desired position by lifting the rear runners 22 above the floor or ground. The spring coils 16 and 17 are strong enough to support the lifting jack with the bottom of its base substantially in line with the under surfaces of the wheels 20 and runners 22, as shown in Fig. 1. By ma-

nipulating the attachment from the rear end thereof, a lifting jack may be very easily and quickly positioned under an automobile or truck with little effort on the part of the 5 operator and without having to stoop or get down onto the floor or ground. During this operation, the wheels 20 and runners 22 support the lifting jack in an upright position and prevent the same from tipping. In case 10 the lifting jack is supported by the attachment out of engagement with the floor or ground, the frame 14 will yield at the spring coils 16 and 17 and permit the jack to rest on the floor or ground when operated to engage an axle or other object to be lifted 15 without straining any of the parts of the attachment.

The above described attachment has, in 20 actual usage, proven highly efficient for the purpose had in view and is very light, strong and durable.

What I claim is:

1. An attachment for lifting jacks comprising a frame having means for attaching a lifting jack thereto, and a supporting 25 wheel for the frame.

2. An attachment for lifting jacks comprising a yielding frame having means for attaching a lifting jack thereto, and a supporting 30 wheel for the frame.

3. An attachment for lifting jacks comprising a frame having means for attaching a lifting jack thereto, said frame having an arm, and a frame-supporting wheel 35 journaled on the arm.

4. An attachment for lifting jacks comprising a frame having means for attaching a lifting jack thereto, said frame having an arm yieldingly connected thereto, 40 and a frame-supporting wheel journaled on the arm.

5. An attachment for lifting jacks comprising a frame having means for attaching a lifting jack thereto, said frame having 45 front and rear supporting elements, one of which is a wheel.

6. An attachment for lifting jacks comprising a frame having means for attaching a lifting jack thereto, said frame having 50 front and rear supporting elements, one of which is a wheel, said elements being yieldingly connected to the frame.

7. An attachment for lifting jacks comprising a frame having means for attaching 55 a lifting jack thereto, a front wheel journaled on the frame, and a rear runner on the frame.

8. An attachment for lifting jacks comprising a frame having means for attaching 60 a lifting jack thereto, a pair of front wheels journaled on the frame, and a pair of rear runners secured to the frame.

9. An attachment for lifting jacks comprising a skeleton frame made up of a pair

of side rods and means for connecting the 65 same and attaching a lifting jack thereto, the front end portions of said rods being downwardly extended to afford a pair of arms, and a pair of frame-supporting wheels journaled on said arms. 70

10. An attachment for lifting jacks comprising a skeleton frame made up of a pair of side rods and front and rear U-bolts connecting said rods and frictionally clamping the same onto opposite sides of a lifting 75 jack, the front end portions of said rods being downwardly extended to afford a pair of arms, and a pair of frame-supporting wheels journaled on said arms.

11. An attachment for lifting jacks comprising a skeleton frame made up of a pair of side rods and front and rear U-bolts connecting said rods and frictionally clamping the same onto opposite sides of a lifting jack, said rods being bent to form 85 spring coils and then extended downward to afford a pair of arms, an axle secured to said arms, and a pair of wheels journaled on the axle.

12. An attachment for lifting jacks comprising a skeleton frame made up of a pair of side rods and front and rear U-bolts connecting said rods and frictionally clamping the same onto opposite sides of a lifting jack, said rods being bent to afford front 95 and rear spring coils and at the former of said spring coils said rods are downwardly extended to afford a pair of arms, an axle secured to said arms, a pair of wheels journaled on the axle, said rods at the rear 100 spring coils having means for attaching the operating connection of a lifting jack thereto.

13. An attachment for lifting jacks comprising a skeleton frame made up of a pair 105 of side rods and front and rear U-bolts connecting said rods and frictionally clamping the same onto opposite sides of a lifting jack, said rods being bent to afford front and rear spring coils and at the former of said spring coils said rods are downwardly extended to afford a pair of arms, an axle secured to said arms, a pair of wheels journaled on the axle, said rods at the rear 110 spring coils being extended and bent to form a pair of runners, and means for securing the operative connection of a lifting jack to the frame side rods.

14. A lifting jack having a projecting handle and provided with a vertically movable supporting wheel, and yielding means 115 downwardly pressing said wheel with sufficient force to normally carry the jack above the floor but to yield and permit the jack to engage the floor when under a load. 120

In testimony whereof I affix my signature.

PAUL E. HAWKINSON.
